UNITED STATES PATENT OFFICE.

LINDSLEY SCHEPMOES, OF HASBROUCK HEIGHTS, NEW JERSEY.

LOCKING MEDIUM FOR DECORATIVE AND OTHER BLOCKS.

1,361,501.

Specification of Letters Patent.

Patented Dec. 7, 1920.

Application filed December 12, 1918. Serial No. 266,410.

To all whom it may concern:

Be it known that I, LINDSLEY SCHEPMOES, a citizen of the United States, residing at Hasbrouck Heights, in the county of Bergen and State of New Jersey, have invented a new and useful Improvement in Locking Mediums for Decorative and other Blocks, of which the following is a specification.

This invention relates to decorative and other blocks which may be used for various purposes such as tiling, inlays, marquetry, wall coverings, stencils, types, printing plates, toys, pasting stamps, decalcomania and other useful, decorative or amusement purposes. Particularly, the invention has reference to a locking unit, block, member or medium capable of being used with media of the nature mentioned for positively locking and interlocking with the same, and also capable of being used for the purposes stated in the foregoing.

In order that my invention may be clearly understood, I have provided drawings wherein:

Figure 1 is a plan view of one of my locking blocks or units;

Fig. 2 is a section of Fig. 1 substantially on the line 2—2;

Fig. 3 is a plan view showing a design made up of blocks or members in the form of isosceles polygons, locked together by a plurality of the locking units or media forming an essential part of my present invention;

Fig. 4 is a plan view showing a plurality of the locking media or units interlocked in accordance with my invention; and

Fig. 5 is a view similar to Fig. 3; but, showing a different form of the locking or interlocking media or units, and also a different form of the blocks interlocked and held together by the locking units.

Primarily, it should be understood that my present invention, from one aspect, consists of a locking or interlocking block, unit, member or medium adapted to be used interchangeably with each other, or with filling blocks, member, units or media having cooperative features of construction adapting them to be used interchangeably with each other and with the locking units. This will be understood from the detail description which follows, and particularly with reference to Figs. 1 to 4.

The locking unit consists of a member 1 of

suitable thickness and area, as shown in Figs. 1 and 2, and may be made of any material found suitable for the particular purpose to which the unit is to be adapted, as set forth in the foregoing. The locking unit 1 is so formed as to provide parallel opposite sides 2 terminating at one end in converging shorter sides 3, forming, with two still shorter sides 4, acute angles, the shorter sides of which constitute the base of a substantially spear-shaped terminal 5 completed by sides 6 producing a right-angle, the vertex of which is indicated at 7. The sides 6 join the sides 4 forming therewith acute angles. Thus the substantially spear-shaped terminal 5 is joined to the body 1 of the unit by a narrow neck 8. At its opposite end, the body of the unit is provided with a recess or opening bounded by two sides 9 constituting a right-angle, the vertex 10 of which is in the longitudinal axis of the unit, in which axis the vertex 7 is also located. The two sides 9 form acute angles 11 with short sides 12 which, in turn, form acute angles 13 with longer sides 14, which, in turn, form acute angles 15 with the parallel sides 2, obtuse angles 16 being formed by the latter and the converging sides 3. Thus, the large end of the block has a substantially spear-head shaped opening corresponding to the spear-head terminal 5, and a neck 17 corresponding to the neck 8, and a flared opening corresponding to the shape of the body of the unit below the neck 8. Stating the features of the unit otherwise, it will be seen that the opposite sides 2 are parallel, the sides 6, 3, 9 and 14 on the same side of the unit are parallel, and sides 4 and 12 on the same side of the unit are parallel.

The form of the unit shown is given for its locking and interlocking value, as well as to provide a symmetrical, interchangeable unit adapted to interlock with others of its kind, as well as with filling units 19, having features of construction adapting them to coöperate with, and interlock with, the said locking units at either or both ends. It will be understood, however, that the exact shape and dimensions of the various members, such as the terminal tongue 5 and the terminal tongues 18, as well as the inner spear-shaped opening formed by the sides 9 and 12, may be varied in form, shape or size, provided the general conformation of the said features of construction are maintained. An example of such variation is

shown in Fig. 5, wherein the tongue or terminal 5^a of the locking unit is shown as being less prominent, or not quite so extensive, in the direction of the length of the unit, this being also true of the inner opening bounded by the walls 9, 12 at the opposite end of the unit. To coöperate with locking and interlocking units of this different form of my invention, I have shown variations in the 10 form of the filling blocks or units 20 which latter are shown to be longer and narrower than the filling blocks 19, of Fig. 3, or to be in the general form of equilateral triangles, in contradistinction to the general form of 15 right-angle triangles, such as shown in Fig. 3. As shown in both Figs. 3 and 5, some of the filling blocks are provided with locking tongues 21 at opposite ends of openings or grooves 22 centrally disposed on one side 20 thereof, while others are provided with locking tongues 23 centrally disposed and bounded by the walls of end openings or grooves 24.

The general forms of locking units and 25 operating filling units, examples of which are shown in the drawings, may be varied to a considerable extent without in any way departing from the general nature and spirit of my invention, the important characteristics of which are illustrated in Figs. 1, 3 and 4.

As shown in Figs. 3, 4 and 5, designs of 30 various character can be formed by variously disposing the interlocking filling and locking units; but, particularly referring to Fig. 3, it will be seen that the units can be disposed so as to produce a design in which a great many filling units 19 are employed, and held together by only four locking 35 units 1, the latter constituting an absolute and positive lock for all the filling units and each other. The extent to which the designs and uses of my locking unit can be varied is illustrated in Fig. 5, wherein many more 40 filling units 19 are employed, with only six locking units 1, which constitute an absolute and positive lock for the filling units and for each other.

As further illustrating the great variation 45 in design and use of my invention, reference is made to Fig. 4, wherein the locking units are shown as interlocked with each other only and as constituting a positive and absolute lock for each other. From this 50 figure, it will be seen that the locking units can be variously extended both lengthwise and laterally, as may be desired, according to the pattern, form or use to which the unit is adapted; that is to say, the two adjacent 55 interlocked units 1 may be extended laterally for pattern or design purposes, and the endwise interlocked units may be extended lengthwise in either direction, to any desired degree, for the purpose of forming 60 borders, edgings, or straight lines, in a gen-

eral design make-up. And it will be understood that both the designs of Figs. 3 and 5 can be extended in all directions by the addition of other filling units and locking units, whereby to produce any desired extent or 70 area of designs or covering surface, according to the use to which the units or blocks are put.

From the foregoing description, it will be understood that my interlocking and filling 75 blocks may be employed for various purposes, as set forth, and that, with surface ornamentations of predetermined character, indefinite, ornamental designs and beautiful effects can be produced adapted for tiling, 80 flooring, wall-paper, wall-linings or coverings, printing types, stereotypes, lithographing plates, stencils, and, in fact, for innumerable purposes; but, the important characteristic of my invention is that I have produced a novel form of locking unit which is a 85 positive lock for itself when a plurality are combined, as well as for itself and each of the filling blocks when combined, regardless of 90 number.

Instead of making the sides of the locking unit join each other to form angles, the sides may be joined by curved lines giving more or less of symmetry and less abruptness to 95 the outline of the features of the unit.

Having thus described my invention, what I claim and desire to secure by Letters Patent is:

1. As an article of manufacture, a locking 100 unit for tiles, blocks, or decorative devices having a spear shaped locking tongue at one end and an open-end locking slot or recess at the other end, which slot or recess is in form the same as the said tongue.

2. As an article of manufacture, a locking 105 unit for tiles, blocks, or decorative devices having a comparatively long body portion, one end of which terminates in a spear shaped locking tongue, and the other end of which is provided with a recess the form of 110 which is substantially the same as that of the said tongue.

3. As an article of manufacture, a locking 115 unit for tiles, blocks, or decorative devices oblong in form and having its parallel longer sides at one end joined by converging sides which terminate in an angular locking tongue, and having its opposite end provided with a recess in form substantially the same as that of said tongue.

4. As an article of manufacture, a locking 120 unit for tiles, blocks, or decorative devices oblong in form and having its parallel longer sides at one end joined by converging sides which terminate in a spear shaped locking 125 tongue, and having its opposite end provided with a recess in form substantially the same as that of said tongue.

5. As an article of manufacture, a locking 130 unit for tiles, blocks, or decorative devices,

having at one end a substantially spear shaped terminal centrally disposed between divergent sides of the unit, and at its other end an opening the walls of which at one end 5 produce a substantially spear shaped figure and at the other end a flared terminal.

6. As an article of manufacture, a locking unit for tiles, blocks, or decorative devices, comprising an elongated body portion having at one end a substantially spear shaped terminal centrally disposed between divergent sides of the unit, and having its other end formed into a similarly shaped opening, the vertex of the terminal angle of 10 which is in the longitudinal axis of the block. 15

7. As an article of manufacture, a locking unit for tiles, blocks, or decorative devices, comprising a body portion narrowed at one

end and extended into a substantially spear shaped tongue, the vertex of which is in the 20 longitudinal axis of the block, and having at its other end an opening in form similar to the said narrowed end and extended tongue, the vertex of the angle of which is in the longitudinal axis of the block. 25

8. A locking unit comprising a body portion, one end of which is formed into a tongue having a plurality of sides forming at least three angles, the vertex of one of which is in the longitudinal axis of the unit, 30 and having its other end provided with a recess bounded by a plurality of sides forming angles corresponding in number to and arranged like those of the tongue.

LINDSLEY SCHEPMOES.
